(57) **CLAIM**

The ornamental design for a connector for a sanitizing machine, as shown and described.

DESCRIPTION

FIG. 1 is a front view of a connector for a sanitizing machine, showing the new design;

FIG. 2 is a rear view thereof;

FIG. 3 is a left side view thereof;

FIG. 4 is a right side view thereof;

FIG. 5 is a bottom view thereof;

FIG. 6 is a top view thereof;

FIG. 7 is a front top perspective view thereof;

FIG. 8 is a front bottom perspective view thereof;

FIG. 9 is a front left top perspective view thereof;

FIG. 10 is a front right top perspective view thereof;

FIG. 11 is a front right bottom perspective view thereof;

FIG. 12 is a front left bottom perspective view thereof;

FIG. 13 is a right side top perspective view thereof;

FIG. 14 is a right side bottom perspective view thereof;

FIG. 15 is rear top perspective view thereof;

FIG. 16 is a rear top right perspective view thereof;

FIG. 17 is a rear top left perspective view thereof;

FIG. 18 is a rear bottom perspective view thereof;

FIG. 19 is a rear bottom left perspective view thereof; and,

FIG. 20 is a rear bottom right perspective view thereof.

The broken lines in the drawings depict portions of the connector for a sanitizing machine that form no part of the claimed design.
